DESIGN FOR A CARTON LUNCHEON TRAY

Walter E. Button, Rye, N. Y., assignor to Canteen Food Service, Not Inc., Chicago, Ill., a partnership comprised of Frank H. Anderson, Louis E. Leverone, Nathaniel Leverone, and Walter E. Swanson, Sr.

Application September 4, 1942, Serial No. 108,133

Term of patent 14 years

To all whom it may concern:

Be it known that I, Walter E. Button, a citizen of the United States, residing at 31 Sussex Gardens, Rye, in the county of Westchester and State of New York, have invented a new, original, and ornamental Design for a Carton Luncheon Tray, of which the following is a specification, reference being had to the accompanying drawing, forming part thereof.

The single figure is a view in perspective of a carton luncheon tray embodying my new design.

The side and end of the luncheon tray not shown in the drawing are substantially the same as the side and the end which are shown.

I claim:

The ornamental design for a carton luncheon tray, substantially as shown and described.

WALTER E. BUTTON.
